CLAIM

I claim the ornamental design for a portable charger for an electric vehicle, as shown and described.

DESCRIPTION

FIG. 1 is a top perspective view showing a portable charger for an electric vehicle of my new design;

FIG. 2 is a front plan view thereof;

FIG. 3 is a side plan view thereof;

FIG. 4 is a side plan view thereof opposite FIG. 3;

FIG. 5 is a rear plan view thereof;

FIG. 6 is a top plan view thereof; and,

FIG. 7 is a bottom plan view thereof.

The broken lines (for example the "LUCID" text and the lower cable) are for illustrative purposes only and form no part of the claimed design.
